[57] CLAIM

The ornamental design for a ski rack, as shown and described.

DESCRIPTION

FIG. 1 is a side perspective view of a ski rack showing my new design in a closed position;

FIG. 2 is a bottom perspective view thereof;

FIG. 3 is an end elevation view thereof;

FIG. 4 is a side perspective view in an open position;

FIG. 5 is a bottom perspective view of FIG. 4; and

FIG. 6 is a side perspective view similar to FIG. 4 but with portions of the support clamp unit omitted for clarity of illustration.

*FIG. 1**FIG. 2*FIG. 3

FIG. 4
